PATENTED MAY 22, 1906.

J. SZCZEPANIK.

PROCESS FOR THE PRODUCTION OF PHOTOGRAPHS IN NATURAL COLORS.

APPLICATION FILED AUG. 16, 1902.

UNITED STATES PATENT OFFICE.

JAN SZCZEPANIK, OF VIENNA, AUSTRIA-HUNGARY.

PROCESS FOR THE PRODUCTION OF PHOTOGRAPHS IN NATURAL COLORS.

No. 821,200.

Specification of Letters Patent.

Patented May 22, 1906.

Application filed August 16, 1902. Serial No. 119,927.

To all whom it may concern:

Be it known that I, JAN SZCZEPANIK, a subject of the Emperor of Austria-Hungary, residing at Vienna, in the Province of Lower Austria, in the Empire of Austria-Hungary, have invented certain new and useful Improvements in Processes for the Production of Photographs in Natural Colors; and I do hereby declare the following to be a full, clear, and exact description of the invention, such as will enable others skilled in the art to which it appertains to make and use the same.

It is already known that a colored positive can be obtained by allowing a celloidin or aristo paper to darken by exposure to light, washing it in a mixture of sulfate of copper and potassium bichromate, and, after drying, exposing it for days under a colored dia-

positive.

In the drawings, Figures 1 to 11 illustrate diagrammatically the steps that take place, and Fig. 12 illustrates a paper used in the process. Fig. 13 is a section showing three superposed gelatin films pressed together, and Fig. 14 is a like view showing a varnish or cement between the layers.

The process that takes place may be explained in the following manner.

The darkened celloidin paper contains all possible colors, of which some fade under the action of certain of the colored rays proceeding from the diapositive. The same result can be obtained when only three non-fast primary colors (as red, yellow, and blue) are present in the film or coating of the paper, for, as is known, any paper which is coated with these three colors is capable of reproducing all the colors of an artificially-made colored diapositive, provided that the coloring materials be non-fast—*i. e.*, capable of fading. Through the red parts of the diapositive there will pass only red rays, which are then absorbed by the particles of yellow and blue coloring material, so that the yellow and blue colors fade, while the red particles of color reflect the red rays, and therefore cannot fade. A red tint, therefore, appears on the paper under the red parts of the diapositive. The action under the differently-colored parts is similar. According to this well-known process it is therefore possible to produce colored prints from a colored artificially-made diapositive, and in order still more to enhance the property of fading the papers are while being prepared immersed in sev-

eral suitable baths—as, for instance, hydrogen peroxid or chlorophyl. The colors or coloring-matters remaining on the paper after printing may, like any non-fast color, be made fast by immersing them in a solution of common salt and sulfate of copper or in copper-ammonium sulfate. Direct photographs cannot be taken with a camera on papers coated with non-fast colors, because owing to the low degree of sensitiveness of the film the exposure would have to last for days; but these papers may be used for printing under a colored diapositive. It has not heretofore been possible to produce real dia-positives in natural colors, but merely substitutes made by a combination of colored strips. Such an artificially-prepared dia-positive is, however, only suitable for experiments. Furthermore, three coloring substances when mixed together will not combine in one medium, (gelatin,) as they change color, diminish in sensitiveness, and reproduce defectively the colors in question. Now according to this invention these disadvantages are obviated and pictures are made in the following manner: Three negatives—namely, the first for red, the second for yellow, and the third for blue—are prepared in the camera through color-filters, as in the three-color-printing process, but without a ruled screen. The three negatives can be made on three separate glass plates; but it is preferable to prepare them in a row on a single plate. By immersing the two end parts of the plate in the corresponding sensitizing media these end parts are rendered suitably sensitive for taking the corresponding color negatives, while the middle part of the plate is ready for the third negative without further preparation.

When printing on paper with three non-fast coloring substances—that is, colors that fade—a negative is obtained from a negative. As, however, a positive picture is desired, three diapositives must be produced from these three negatives. The diapositives obtained are then printed on the three-colored paper in such a way that each of them is exposed to rays of a color forming the color complementary to that for which the dia-positive is intended. The dia-positive for red, for instance, must cause only the red coloring-matter to fade on the three-colored paper at all its transparent parts. At these parts the paper must be exposed to the action of the rays of the complementary color—

namely, green—which cause the red color parts to fade, but are reflected by the other colors, which therefore remain unchanged. Thereupon the diapositive for yellow is printed under the action of violet rays, and, finally, the third diapositive for blue is printed under the action of the orange-colored rays. An image in natural colors then appears on the film or coating of the paper.

Let us suppose we wish to make a colored print of Fig. 1, containing red, yellow, and blue fields marked separately R, Y, and B, the sensitive film *l*, Fig. 2, on which it is to be printed, containing the three colors mixed and capable of being fixed when suitably printed and also having the property of fading under differently-colored light. From the object, Fig. 1, three negatives *h i j*, Figs. 3, 6, and 9, made by the aid of color-filters, from each of which a diapositive *d e f* is formed, Figs. 4, 7, and 10. This diapositive *d* for red is then placed upon the sensitive paper, and over the diapositive is placed a filter *m*, giving the complementary colored light, green. The portion of the paper *a*, Fig. 5, is thus covered or shielded from these rays, while the remaining portions are exposed to it, so that the red color in or red reflecting particles in the parts *b* and *c* are caused to fade, the yellow and blue color particles not being affected by the green light. Then the diapositive *e* for yellow is placed on the paper and registered and provided in like manner with a filter *n* to give the complementary color, in this case violet, Fig. 7. The yellow or yellow-reflecting particles on the sensitive surface will then be caused to fade, excepting in the part *b*, covered by the diapositive, and produce the effect, Fig. 8. Finally the sensitive medium, Fig. 8, has registered on it the diapositive *f* for blue and similarly covered with a filter *o*, capable of giving complementary-colored orange light, so that all the blue in the transparent portion of the diapositive will fade, thereby giving a reproduction in color, Fig. 11, like the original, but a mirror-picture. When the three coloring-matters are mixed together on the paper—for instance, in a film of gelatin—it will be found, as hereinbefore described, that the mixed coloring substances change somewhat and are less sensitive than if they were used separately. Now this disadvantage is obviated according to this invention by applying the colors side by side upon the color-carrier—as, for instance, gelatinized paper. Thus, for example, the paper can be ruled with non-fast pigments in such a way that a red, then a yellow, and then a blue line always lie side by side in the same order, as shown in Fig. 12, where *r* represents the red line, *g* the yellow line, and *b* the blue line on a surface *k*, or these colors can be applied side by side in the same order in any other desired or convenient manner. Finally, colored

photographs can also be produced on paper, wood, leather, and the like by coating these materials with three differently-colored layers of gelatin placed one above the other. This can, for instance, be effected by stripping three gelatin films, colored with different anilin dyes and made sensitive to light by means of chlorophyl or hydrogen peroxid, as shown in Fig. 13, from three glass plates and laying these films one above another on paper and pressing them together in such a way that they remain in contact. The same result can be obtained by applying to the paper first a red-tinted gelatin coating, then a layer of water-glass or varnish as an insulating medium, then a yellow gelatin coating and another layer of water-glass or varnish *g*, and, finally, a blue gelatin coating, as shown in Fig. 14. The water-glass or varnish layers serve to prevent the gelatin coatings from intermingling. Instead of gelatin any other suitable material—as collodion, albumen, or size—can be used as a color-carrier. The three-colored films thus produced are used as follows: A diapositive for red must be printed on the lowest or red film under a green filter. The two upper films—namely, the yellow and the blue—act as a substitute for the green filter. Nevertheless a separate green filter is laid over them, so that the white light, which of course contains red rays, cannot cause the colors of the upper films to fade. The green rays of the filter do not act, however, on the two upper films, (yellow and blue films,) but cause only the lowest or red film to fade. Subsequently the yellow film in the three-film paper is printed under a violet filter, and, finally, the blue film is printed under an orange filter, diapositives for the corresponding colors of the films being used. In order that the three diapositives may be accurately superimposed, suitable printing-frames must be used. The process is or may be the same or similar in the case of fabrics made as described.

When diapositives are used in a row on one single plate as hereinbefore described, the different diapositives can by simply pushing the plate in one direction be more easily caused to register than when three separate diapositives are used. The diapositives produced by printing from negatives (provided that they are made without reversing prisms) are normal; but the colored positive which is obtained from the diapositive is reversed—that is, it forms a mirror-picture. If, however, this positive produced on a suitable transparent material, as glass, so as to form a colored diapositive, it follows from what has hereinbefore been stated that a normal picture can be produced by printing it on paper provided with three colors, as aforesaid. In doing this no filter will be required, since the glass or diapositive will itself act as a filter. Thousands of copies can

be made without difficulty without any filter from diapositives made in this way.

Having thus described my invention, what I claim as new therein, and desire to secure by Letters Patent, is—

1. The process of making colored photographs, which consists in producing photographic plates of the object having different color values, printing such plates on a paper containing colored particles and thereby causing those colors to fade not corresponding to the color value of the plates, substantially as described.

2. The process of making colored photographs, which consists in producing a plurality of photographic plates of the object having different color values, printing such plates in registered succession on actinic paper containing non-permanent colors, thereby causing those colors to fade not corresponding to the color value of the plate, substantially as described.

3. The process of making colored photographs, which consists in providing three registrable negatives produced with the aid of color-screens, obtaining diapositives from said negatives of different monochrome values and printing each monochrome diapositive, on an actinic paper containing fadable primary colors, under the influence of lights of color complementary to the color of the reflective screens used to produce the diapositives, substantially as described.

4. The process of making colored photographs, which consists in producing three registrable negatives with the aid of screens for primary colors, producing diapositives from said negatives, printing the diapositives on actinic paper containing fadable primary colors, each positive during printing being subjected to light complementary to that represented by said diapositive, substantially as described.

5. The process of making photographs,

which consists in producing registrable monochrome diapositives having densities proportional to the primary colors, producing a transparent mirror-print in three colors from said diapositive and then printing from said transparent print on actinic paper containing fadable primary colors in recurring series, substantially as described.

6. The process of making photographs, which consists in producing three superposed transparent actinic sheets each colored with a fadable actinic color, successively printing on said sheets registrable monochrome diapositives having primary color values, subjecting each diapositive while covering the actinic sheets to light complementary to that which said diapositive represents, fixing the colors in the actinic sheets after exposure, then printing from the mirror-picture so formed on actinic paper containing fadable primary colors and fixing the print so formed, substantially as described.

7. The process of making photographs, which consists in producing registrable negatives of an object having primary color values, producing diapositives from said negatives, forming a superposed transparent three-ply film in fadable actinic primary colors, printing such diapositives on the film under the influence of light complementary in color to that represented by the respective diapositives, fixing the transparent mirror-print so made and then printing from said transparent print on actinic paper ruled with fadable primary colors, and fixing the latter print, substantially as described.

In testimony that I claim the foregoing as my invention I have signed my name in presence of two subscribing witnesses.

JAN SZCZEPANIK.
